DESIGN FOR A BODY FOR BABY CARRIAGES OR THE LIKE

Michael Edward Berry, Toledo, Ohio, assignor to
The American-National Company, Toledo,
Ohio, a corporation of Ohio

Application January 29, 1934, Serial No. 50,534

Term of patent 7 years

To all whom it may concern:

Be it known that I, MICHAEL EDWARD BERRY, a citizen of the United States of America, residing at the city of Toledo, in the county of Lucas, in the State of Ohio, have invented a new, original, and ornamental Design for a Body for Baby Carriages or the like, of which the following is a specification, reference being had therein to the accompanying drawings, forming a part thereof, wherein:

Figure 1 is a perspective view of a body for baby carriages embodying my invention;

Figure 2 is a top plan view of the body illustrated in Figure 1;

Figure 3 is a side elevation of the body illustrated in Figure 1;

Figure 4 is a rear elevation of the body;

Figure 5 is a front elevation of the body;

Figure 6 is a horizontal sectional view taken on the line 6—6 of Figure 3 through the one-piece metal sheeting of the body.

I claim:

The ornamental design for a body for baby carriages or the like, substantially as shown.

MICHAEL EDWARD BERRY.
